UNITED STATES PATENT OFFICE.

LEONHARD KELLENBERGER, OF ST. GALLEN, SWITZERLAND.

APPARATUS FOR GRINDING CRANK SHAFTS.

Application filed June 29, 1923. Serial No. 648,574.

To all whom it may concern:

Be it known that I, LEONHARD KELLENBERGER, a citizen of the Republic of Switzerland, and resident of St. Gallen, in the Canton of St. Gallen, Switzerland, have invented certain new and useful Improvements in Apparatus for Grinding Crank Shafts, of which the following is a specification.

The present invention relates to an improved apparatus for grinding crank-shafts. The grinding thereof is effected by means of comparatively small grinding-wheels which by the aid of a pivoted supporting arm are adapted to be introduced between the crank-webs. Though it has been previously proposed to construct such apparatus, they all have the drawback that their width is too great to permit of the grinding of the pins of very small or narrow cranks, and since the bearing surfaces of the crank-shafts of up-to-date small motors are small, the width of the grinding apparatus of the kind described must of necessity be as small as possible. It is certainly old in known grinding apparatus to mount belting or other driving-gear between and centrally of two grinding-wheels, yet, in order that the latter have sufficient grinding power it is essential that the driving belt is of a certain width with the consequent disadvantage, however, that the smallest possible width of the crank-pin or stud to be ground is comparatively large. There are other known grinding devices provided with one grinding-wheel only and with a driving belt mounted adjacent thereto, the drawback of these devices being that upon the tilting over of the grinding-wheel the belt requires to be detached and the wheel removed from the pin.

My invention has for its object an improved method and apparatus which makes it possible by means of two grinding-wheels to grind even very short crank-studs, the mounting of the said wheels being such as to require a minimum of room. The accompanying drawings illustrate one form in which the invention may be embodied, the grinding apparatus in this case being shown as mounted on a lathe and adapted to be driven by the usual gear. It will be understood, however, that the apparatus could also be constructed to form an independent machine. In the said drawings:—

Fig. 1 shows a plan of the grinding apparatus;

Fig. 2 is a side view, and

Fig. 3 a front view thereof.

Fig. 4 represents a sectional view of the supporting and bearing parts;

Fig. 5 is a view similar to that in Fig. 2 but with the several parts in different positions, and

Fig. 6 shows a modification of the mounting of the two grinding-wheels.

Referring to these drawings, *a* denotes the upper and left-hand grinding-wheel and *b* the lower right-hand grinding-wheel. These wheels are arranged close to each other but not on the same axle. Theoretically they could also be mounted side by side, in such a way, that they take up a width approximately double that of one of the wheels, though in practice it would then be necessary to leave some small space between them; or, the two wheels could be mounted apart and so that their edges are in a plane. Journaled close to the upper and left-hand grinding-wheel *a*, on a common axle therewith, is a grooved pulley *c* and similarly mounted relative the grinding-wheel *b* is a grooved pulley *d*, the arrangement of the two wheels and the two pulleys hereby being such, that the pulley of one of the grinding-wheels is located at the rear of the other grinding-wheel, while the latter is rearwards of the other pulley, Fig. 3. Moreover, the pulley *c* mounted adjacent to the grinding-wheel *a* is of such a width, that laterally it does not project beyond the grinding-wheel *b* situated above it, while the pulley *d* mounted adjacent to the grinding-wheel *b* does not extend over the width of the grinding-wheel *a*. Provision is further made of a supporting arm *e* for the grinding-wheels and pulleys, this arm being pivoted as shown at *f*, Figs. 2 and 5. A belt or driving cord *i* led over the pulleys *c* and *d* lies slightly off the centre line *x* of the arm *e*, Fig. 4, for the purpose of neutralizing the pressure or strain on the grinding-wheel. The bending strain of the arm *e* is therefore wholly or nearly eliminated. Owing to the arrangement crosswise of the two grinding-wheels and the two pulleys respectively, the considerable advantage is gained that the driving cord *i* is driving one of the grinding-wheels only, the other wheel running loosely. The construction described is moreover such as to permit of the working alternatively of one or the other of the grinding-wheels *a* and *b*.

To this end each grinding-wheel may either be journaled in a support or made adjustable in a straight line, or both grinding-wheels may, as previously mentioned and as illustrated in Fig. 2, be made to bear in a pivoted arm *e*, and so that they are always exactly at the same distance *r* from the pivot *f*. The latter may be fixed in any suitable way, for instance in a slotted plate which, in turn, is mounted on the slide-rest of the lathe. Thus, if the arm *e* is swung into the position, Fig. 2, the wheel *a* is in working position, while upon the swinging over of the arm *e* into the position, Fig. 5, the other grinding-wheel *b* is in working position.

The adjustment of the arm *e* is brought about by means of a spindle *g* and by the clamping fast of a screw *h* with handle. The adjustment may, however, be effected by any other suitable and known mechanism, for instance by the aid of eccentrics, cams, or levers, or by a raising and lowering device with stopping means. The rotation of the two grinding-wheels can, of course, also be effected by two separate belts or cords, but according to the preferred construction the two grinding-wheels are actuated by the single driving cord *i*, which is itself driven by a larger sized grooved pulley *k*, adjacent to which are mounted a loose and a fast pulley *l* and *m*. The pulley *k*, receiving its rotary movement from the pulley *l*, transmits such movement by means of the cord *i* and an intermediate roller *n* to the pulley *c*, whence the cord *i* is led over to the guiding roller mounted at *o*. The latter is arranged obliquely in such a manner, Fig. 3, that the said cord runs from the pulley *c* in a slanting direction over to the other pulley *d*. From there the cord is led back to the larger pulley *k*. By this simple device it is possible to actuate both the grinding-wheels.

In operation the apparatus works as follows: Assuming the grinding to be done first by the grinding-wheel *a*, the same is brought into the position, Fig. 2, and one half of the crank-stud caused to be ground. The arm *e* and consequently the grinding-wheel *b* are thereafter adjusted into the position, Fig. 5, and the other half of the crank-stud ground.

And in order to allow the cord *i* to be tightened, the guiding roller at *o* may be made adjustable, or, as an alternative, the pulleys *k*, *l* and *m* may be mounted so as to be capable of adjustment eccentrically of the pivot *f*.

From Fig. 4, illustrating a section through the supporting and bearing parts for the grinding-wheels, it will be seen that the pulleys adjacent thereto each comprise two parts, the part *p* being in the form of a flanged disc with a central pin, while *q*

designates a guide-ring fitted on the end of the said pin and serving as a means to prevent the detachment of the bearing on the one hand and, conjointly with the flanged part *p*, forming the grooved pulley for the cord *i* on the other hand. Mounted between the two parts *p* and *q* and receiving the aforesaid pin is the pivoted arm *e*, which thus carries the whole of the device last described. Both the grinding-wheels *a* and *b* may also be obliquely mounted on the arm *e* as illustrated diagrammatically in Fig. 6, the purpose of this arrangement being to facilitate the grinding of the rounded off ends of the crank-stud.

What I claim as new and desire to secure by Letters Patent is:—

1. In the herein-described apparatus applicable to lathes and other machine tools and adapted for grinding the crank-studs of crank-shafts, the combination, with an arm pivotally mounted on the slide-rest of the lathe, of two rotatable grinding-wheels journaled in the free end of the said pivoted arm and mounted laterally and crosswise of each other and on separate axles, a driving pulley adjacent to each of the grinding-wheels and secured to its axle, each of the driving pulleys being in a plane with the opposite grinding-wheel and corresponding with its width, and means to rotate the said pulleys and grinding-wheels.

2. In the herein-described apparatus applicable to lathes and other machine tools and adapted for grinding crank-shafts and more particularly the crank-studs thereof, the combination, with an arm pivotally mounted on the slide-rest of the lathe, of two rotatable grinding-wheels journaled in the free end of the said pivoted arm and mounted laterally and crosswise of each other and on separate axles, a grooved pulley adjacent to each of the grinding-wheels and secured to its axle, each of the said pulleys and grinding-wheels being at the same distance from the pivot of the arm; means to rotate the pulleys and grinding-wheels; and mechanism for swinging the arm about its pivot to cause the grinding-wheels to be alternately brought into working position.

3. The combination, in the herein-described apparatus applicable to lathes and adapted for grinding the crank-studs of crank-shafts; of two grinding-wheels mounted laterally and crosswise of each other on separate axles; a grooved pulley adjacent to each grinding-wheel and secured to its axle, each of the said pulleys being in a plane with the opposite grinding-wheel and corresponding with its width, and each pulley comprising two parts, namely, a flanged disc with a central pin, and a guide-ring fitted on the end of the pin; a driving cord leading over and between the flange

of the disc and the guide-ring; an arm pivotally mounted on the slide-rest of the lathe and also arranged between the said flange and the guide-ring and forming a bearing for the aforesaid central pin and pulleys and grinding-wheels, the centre line of the pivoted arm lying slightly off the axis of

the driving cord; means for adjusting the arm about its pivot; and means for actuating the driving cord and cause the rotation of the grinding-wheels, all substantially as and for the purpose set forth.

LEONHARD KELLENBERGER.
